MACHINES FOR FORMING FOLD LINES IN
BOARDS OR SHEETS

Wilfred Kirby, London, and Flavius Kingsford Daniels,
Dartford, England, assignors to Vickers-Armstrongs
Limited, London, England

Application July 6, 1954, Serial No. 441,474

Claims priority, application Great Britain July 6, 1953

1 Claim. (Cl. 93—58.1)

This invention relates to machines for forming fold lines in boards or sheets composed of fibrous materials such as used in the manufacture of boxes, containers, cartons and the like.

Machines are already known for producing fold lines in boards or sheets, such machines possess the disadvantage that they either rely upon very large moulding pressures to produce a fold line, or else rely upon the alteration of the physical dimensions of the blank for the purpose of drawing material laterally into the produced fold line. With existing machinery it is therefore difficult to operate upon a blank so as to produce therein simultaneously several spaced fold lines.

In accordance with the invention, a machine for producing fold lines in board or sheet blanks made of fibrous material, includes at least one pair of rotary folding members which peripherally inter-engage to form a nip, the arrangement and construction of said members being such that when a sheet or board passes between the nip a fold line is produced by forming shear slip planes in the board or sheet along the fold line.

For a better understanding of the invention and to show how the same may be carried into effect, reference will now be made to the accompanying drawings in which,

Figure 1 is a perspective elevation of a bending and creasing machine,

Figure 2 is a part sectional elevation to an enlarged scale of one of the carriages of the machine of Figure 1,

Figure 3 is a part sectional side elevation of the carriage of Figure 2,

Figure 4 is a part section on IV—IV of Figure 2,

Figure 5 is a part sectional plan taken in the line V—V of Figure 3.

Referring to the drawings, the machine shown therein has a bed 1 from which pillars 2 (only one of which can be seen in Figure 1), extend upwardly for the support of a receiving table 3 for blanks 4 of fibrous material. The blanks 4 may be fed forward over the table 3 towards a horizontal longitudinal opening 5, bordered above by a horizontally extending rail 6, and below by a parallel similar rail (not shown in Figure 1). The rails serve to support slidably between them several carriages 8, the carriages are effectively divided into two parts, 8A and 8B so that a blank may be fed through the carriage. Each one of the carriages 8 supports rotary forming members 9, 10, and 11. It will suffice for the present purpose to describe the arrangement of one of these carriages 8.

One such carriage 8 is arranged for sliding between the opposed rails 6 and 7 with the aid of a rack and pinion mechanism 12A and 12B at the top and bottom respectively of the carriage.

The rack and pinion mechanism 12A mounted upon the upper rail 6 consists of a pinion wheel 15 engaging with a rack 13 secured to the rail 6 by bolts 14 (only one of which is shown). The pinion wheel 15 is secured to one end of a shaft 16, which latter is journalled in a bearing 17 formed in an upstanding part 18 of the frame 19 of the upper part 8A of the carriage 8. A bush 20 having an

2

annular flange 21 is secured on the other end of the shaft 16 by a key 22. A pinion wheel 23 is mounted on the bush 20 and is secured thereto by means of bolts 21A passing through the flange 21. The pinion wheel 23 engages with a worm wheel 24 mounted upon a shaft 25. The pinion wheel 23 and the worm wheel 24 are located within a housing 26 formed in the part 18. A plate 27 is provided for closing the housing 26, and is secured to the walls of the housing by means of bolts 28. The plate 27 has a boss 27A on which is carried a ring 29 having a lever 29A extending laterally therefrom. A further plate 30 having a slot 30A is carried on the boss 27A and this plate is secured to the plate 27 by bolts 30B. The plate 30 has graduations 30C and the graduations 30C cooperate with the projection 31. The lever 29A carries a projection 31 which protrudes through the slot 30A. A graduated dial 32 is mounted upon the shaft 16 so that it bears against one end of the bushing 20, the dial being held in position by means of a locking nut 33, screwed onto a threaded part 34 on the end of the shaft 16. The graduations on the dial 32 cooperate with the projection 31.

The worm wheel 24 is keyed (by a key 43) to the shaft 25 such that the shaft may move axially of the worm wheel, but the latter cannot rotate about the shaft. The shaft 25 is vertical and is mounted on bearings provided in the frame 19. The upper end of the shaft 25 has a collar 35, the lower surface 36 of which abuts against the bottom of a recess 37 in the frame 19. The lowermost end of the shaft 25 is formed with an annular flange 38 in which there is formed a transverse groove 39. A coiled spring 40 is provided upon that part of the shaft 25 which extends beyond the surface 41 of the frame 19. The spring 40 bears against the upper surface 42 of the annular flange 38 and against the surface 41 so as to urge the lower surface of the collar 35 against the bottom of the recess 37.

The lower rack and pinion mechanism 12B consists of a rack 44 secured to the rail 7 by bolts 45 (only one bolt 40 being shown). A pinion wheel 46 engaging with the rack 44 is mounted upon a shaft 47. The shaft 47 is rotatably mounted in a bearing formed in a part 48 of the main frame 49 of the part 8B. A pinion wheel 50 is secured to the shaft 47 by a key 51, and is maintained in position by a locking nut 52 threaded on to a screwed portion 53 on the shaft 47.

The pinion wheel 50 meshes with a worm wheel 54 carried upon a shaft 55. A key way 56 is formed longitudinally of the shaft 55 and a key (not shown) is provided which engages in the key way 56 and a co-operating key way (not shown) in the wheel 54. Hence the shaft 55 is slideable axially through the wheel 54 but must always rotate with the wheel 54.

The shaft 55 is vertical and is journalled at its upper end in a bracket 57 formed in the upper part of the frame 49. The lower end of the shaft 55 is similarly journalled in a further bracket 58 formed on the lower part of the frame 49. A spring 59 is threaded upon that part of the shaft 55 which is between the brackets 57 and 58. The upper end of the spring 59 bears against the lower surface 60 of the bracket 57, whilst the lower end of the spring 59 bears against the upper surface 61 of a collar 62, secured to the shaft 55 by a pin 63. The spring 59 acts so as to urge the collar 62 into abutment with the upper surface 64 of the bracket 58, i. e. the spring 59 urges the shaft 55 downwardly.

The upper end of the shaft 55 is formed with a flange 65 upon the upper of which is formed a rib 66. The rib 66 is so dimensioned as to co-operate in the recess 39 in the flange 38. The lowermost surface 67 of the flange 65 abuts against the upper surface of the bracket 57.

The pinion wheel 50 and the worm wheel 54 are en-

closed within a housing 68 formed in the frame 49. A plate 69, for closing the housing 68, is secured to the walls of the housing by bolts 70 (only one bolt being shown). The lower end of the shaft 55 is apertured to receive the shank of a plug 55A. The head of the plug 55A serves as an abutment surface for co-operating with a horizontal bar (not shown) disposed immediately below the shafts 55 of all the carriages 8. The bar is arranged to be moved upwardly by means not shown so that when it engages with the plugs 55A, all the plugs 55A, and hence all the shafts 55 are moved upwardly.

In order simultaneously to traverse the carriage portions 8A and 8B, the lower shaft 55 is moved upwardly with respect to its bearing brackets 57 and 58 until the rib 66 engages with the recess 39, the parts 8A and 8B thereby becoming coupled together. Rotation of the shaft 25 by means of the handle 107 therefore causes the shaft 55 also to rotate. Rotation of the shafts 25 and 55 turns the worm wheels 54 and 24 and these rotate the wheels 23, 15, 50 and 46. Rotation of the wheels 15 and 46 causes the carriage 8 to be moved along the horizontal rails 6 and 7.

The extent of the lateral transverse may be measured by reference to the indicating dial 32 and projection 31.

A main driving shaft 71 passes through the carriage part 8B, such shaft having a longitudinal key-way 72. An annular member 73 is mounted rotatably within the carriage part 8B and is disposed upon the driving shaft 71 with a key 74 entering the longitudinal key-way 72. A second annular member 75, similar to the first is also supported rotatably in the carriage part 8B and lies upon the driving shaft 71. The second annular member 75 is not however, keyed to the shaft 71, but is connected rigidly to the first annular member 73 by bolts 76 extending between the two members 73 and 75. The annular members 73 and 75 are shrouded by the frame 49 and a side member 76A which are secured together by bolts 76B. Ball races 76C are provided between the member 75 and the frame 49 and between the members 73 and 76A. An annular forming element 77 is located between the two annular members 73 and 75, the bolts 76 passing through the element 77 so as positively to prevent any movement of the element 77 relative to either of the annular members 73 and 75. The outer peripheral edge 78 of the annular forming element 77 is tapered so as to be of substantially V-section with the apex of the V rounded. In this particular example, the angle of the V is about 60 degrees. It is however to be understood that this angle is not critical. Two channel section rings 79 and 80 are located one on either side of the forming element 77 in such a way that the channels 81 and 82 of the rings 79 and 80 respectively are opposed and lie one on either side of the element 77. The webs 83 and 84 of the rings 79 and 80 lie in planes parallel to the general plane containing the annular forming element 77, and the flange portions 85 and 86 of smaller diameter of the rings engage upon the flat surface 87 of the element. The flange portions 88 and 89 of greater diameter terminate upon the peripheral edge of the forming element 77 and are themselves bevelled so as to fit upon the tapering annular peripheral edge 78 of the forming element 77. Thus the two rings 79 and 80 shroud the forming element 77 except for the extreme peripheral portion 90, i. e. the portion near to the rounded tip of the V-section. When the assembly of the two rings 79 and 80 and forming element 77 is viewed from the outside, the outer curved surfaces of the rings 79 and 80 appear to be in alignment and separated by the projecting peripheral portion 90 of the forming element 77. Preferably these outer curved surfaces of the rings 79 and 80 slope gently away from the peripheral edge 78 of the forming element 77 so that they are of greater radius near to the forming element 77 than in parts of such surfaces more distant from the forming element.

The rings 79 and 80 which shroud the forming element

77 are forced into intimate contact with the forming element 77 by circular pads 91 and 92 placed directly in contact with the rings and urged into such contact by springs 93. The pads 91 and 92 and the springs 93 are all carried by the described two annular members 73 and 75, so that the assembly consisting of the forming element 77, the two rings 79 and 80, the circular pads 91 and 92 and the springs 93, rotates in accordance with rotary motion imparted to the main driving shaft 71.

The upper part 8A of each carriage 8 has a shaft 94 the axis of which is contained in a plane above and parallel to the horizontal plane containing the main driving shaft 71, the axis of such fixed shaft 94 being however directed perpendicularly to the axis of the main driving shaft 71. The axis of the shaft 94 is contained in a vertical plane which is the medial plane of the described lower forming element 77. Two hangers 95 and 96 are mounted upon the shaft 94 and are adapted to be rocked about such shaft with the aid of two upstanding yokes 97 and 98 formed on the hangers 96 and 95 respectively. Movement of each yoke causes corresponding rocking motion of its particular hanger. The two yokes 97 and 98 engage upon two eccentric portions 100 and 101 respectively of opposite eccentricity on shaft 99 so that the turning of the eccentric shaft 99 in the one direction or the other, produces motion of the yokes 97 and 98 to the same extent, but in opposite directions. The upper carriage part 8A has mechanism 102 for adjustably rotating the eccentric shaft 99 in either direction. The mechanism 102 consists of a shaft 103 journalled in a bearing 104 formed in the upstanding part 18 of the frame 19. The shaft 103 has an annular flange 105 formed at approximately the centre thereof. The upper surface of this flange bears against the lower surface 106 of the bracket 30 in which the bearing 104 is formed. A collar 103A is secured to the shaft 103 by a pin 108. A handle 107 is provided for fitting onto the upper end of the shaft 103, this upper end being of square section. The lower portion 109 of the shaft 103 is threaded, and carries thereon a slide block 110. The slide block 110 has a square cross-section, and is entered in a slot 111 in the frame 19. The slide block 110 is dimensioned so that it is a sliding fit within the slot 111. The block 110 has a rectangular recess 112 formed therein, the direction of the recess being transverse to the axis of the shaft 103. A pin 113 is entered in the recess 112, the pin 113 being dimensioned so that it can slide in the recess 112. The other end of the pin 113 is entered in one end of a link 114, the other end of the link 114 being secured to the end 115 of the shaft 99, by a pin 116.

A second link 117 has one end thereof mounted on the end 115 of the shaft 99. The link 117 is located between the link 114 and the frame 19. The other end of link 55 117 has an arcuate slot 118 through which a stud 119 projects. The stud 119 is mounted in a plate 120 which is secured to the frame 19 by screws 121. The plate 120 has a scale 120A engraved thereon, the scale reading from 0 to 8. A pointer 122 integral with the link 117 operates with the scale. The link 117 may be locked relative to the plate 120 by means of a nut 124 threaded on the stud 119.

A member 125 is interposed between the frame 19 and the link 117. The shaft 94 is mounted, at one end thereof, in the member 125 and is mounted at its other end on a yoke 126. The member 125 has a substantially rectangular aperture 127 cut therein through which aperture 127 the end 115 of the shaft 99 passes. The link 117, has a spigot 117A which is eccentric with respect to that bore of the link 117 which receives the shaft end 115. The outer diameter of the spigot 117A is in contact with the member 125 at the top and bottom of the aperture 127. By rotating the link 117, within the limits of the slot 118, the member 125, and consequently the shaft 94, can be moved up or down relative to the shaft end 115. To set

the separation between the upper and lower rotary folding members, the link 117 is turned about the shaft end 115 until the pointer 122 co-operates with a desired graduation of the scale 120A. For setting up the apparatus the shaft 94 may be moved up and down relative to the member 125 by means of an adjusting screw 128, the latter being intended to be operated by means of a tommy bar. The yoke 126 is formed on the frame 19 and carries the shaft 94 by means of a pin 129, the direction of the pin 129 being transverse to the axis of shaft 94. It will be seen that, by moving the member 125 in a vertical direction, the shaft 94 swings about the pin 129, whereupon the members 10 and 11 are raised or lowered with respect to the frame 19.

The depending end of each hanger 95 or 96 is formed as a box-like structure and each box receives a composite upper forming element 131 and 132 respectively. A hanger together with a composite upper forming element forms one of the rotary forming members, i. e. member 10 or 11.

Each composite upper forming element 131 (or 132) comprises two forming discs 133 and 134 (or 135 and 136). The discs lie side by side in their respective boxes. The peripheral outer edges of the discs forming a composite element are turned towards one another so that the assembly seems to consist of a single disc. Each composite element 131 or 132 has its outer periphery tapered this being effected by beveling each of the two discs forming the composite. The angle of bevel of the two discs forming the composite is not the same so that the one disc has a blunter edge than the other, e. g., disc 133 or 135 has a blunter edge than disc 134 or 136. The more sharply bevelled disc 134 or 136 has an outer periphery of slightly greater diameter than the other disc (133 or 135). The discs 135 and 136 are mounted by means of ball races 137 and 138 respectively upon a shaft 139. The shaft 139 has a radially directed flange 140 which is located at the centre of the shaft, and which serves to space apart the discs 135 and 136. The shaft 139 is journaled in bearings 141 and 142, the bearing 142 being formed in a plate 143 secured to the hanger 96. The discs 133 and 134 are similarly mounted in the box of the hanger 95.

The two hangers 95 and 96 which extend from the shaft 94 support their respective boxes so that these boxes lie substantially on either side of the vertical plane containing the shaft 94. The axis of rotation of each composite element is inclined with respect to the last mentioned vertical plane so that the portions of said axis remote from the plane are at a lower level than those near to the plane. The inclinations are such that both of the composite forming elements are, at their lowest points, closely adjacent one another and effectively lie on either side of the extreme peripheral portion 90 of the lower forming element 77.

To move the forming members 10 and 11 towards and away from each other the shaft 102 is rotated by turning the handle 107, whereupon the slide block 110 is moved either upwardly or downwardly depending upon the direction of rotation of the handle 107. In either case movement of the block 110 is transmitted to the link 114 which latter rotates the shaft 99, and causes the yoke arms 97 and 98 to move in opposite directions by virtue of the oppositely directed eccentric portions 100 and 101 so that the members 10, 11 are swung towards or away from each other. A scale 130 is provided upon the frame 19, and a pointer 110A on the block 110 co-operates with this scale. It will be realised, therefore, that the scale 130 and pointer 110A afford a means for indicating the distance between the members 10, 11. It is not desirable that there should be a point common to the co-operating edges of the composite elements 131 and 132 and the lower forming element 77. Hence as shown in Figure 2, the vertical plane containing the axis of rotation of the composite element 131 is spaced a horizontal distance

away from the vertical plane containing the main driving shaft 71 on the one side of such plane, whilst the other axis of the composite element 132 is similarly spaced on the other side of the vertical plane containing the driving shaft 71.

In the employment of the machine having one of the described carriers 8, according to the thickness of the board or sheet, so the composite forming elements 131 and 132 are set. In the case of progressively increasing sheet thickness then progressively the hangers 95 and 96 are swung apart and the effective edges of the composite forming elements 131 and 132 are both raised from the co-operating lower forming element 77. After an appropriate adjustment has been made according to board thickness, the blank 4 is fed through the carrier 8 whilst the main driving shaft 71 is rotating the lower forming element 77. In passing between the upper and lower rotary forming members 9, 10, 11 a fold line is imparted to the blank 4. It is to be noted that the lower forming member 9 is self-compensating for differences of thickness of a single blank 4, in the sense that the shrouding rings 79 and 80 can be forced downwards by the blank 4 itself, thereby revealing a larger part of the edge 78 of the lower forming element 77.

As the machine has several of the described carriers arranged side by side several fold lines can be simultaneously made in the same blank. It will be appreciated that the carriers need not be mounted side by side in a line that is transverse to the direction of movement of the blank. If so desired certain carriers could be mounted one behind the other with reference to the intended direction of movement of the blank.

When carriers are mounted one behind the other it is necessary to align the carriers with respect to each other. The alignment of any one pair of carriers is effected as follows: The projection 31 on the lever 29A on the front carrier 8 (with respect to the direction of movement on the blank) is set to the zero of the graduations 30C on the plate 30. The nut 33 is loosened and the dial 32 is turned until its zero graduation co-operates with the projection 31, after which the nut 33 is tightened.

The lower part of the carriage (i. e. part 8B) is then set so that the peripheral portion 90 of the lower forming element 77 is centrally disposed between the composite upper forming elements 131 and 132. When so disposed the rib 66 and the transverse groove 39 are in alignment so that upward movement of the shaft 55 would cause them to engage.

The lower carriage part 8B of the rear carriage (i. e. the carriage disposed behind the said front carriage) is then positioned by aligning the lower forming element 77 thereof with the lower forming element 77 of the front carriage. The upper part of the rear carriage is then set, with respect to the lower forming element 77 of this carriage, so that this element 77 is symmetrically located between its associated composite upper forming members 131, 132, after which the projection 31 on the lever 29A and the dial 32 of the rear carriage are set in the same way as those of the front carriage.

When it is desired to produce two fold lines which are closely adjacent to each other, the front and rear carriages are adjusted along the rails 6 and 7. Thus, for example, if the graduations are in metric measurement, and it is desired to make two fold lines which are 8 mm. apart, the lever 29A of the front carriage is moved so that the projection 31 coincides with graduation 4 on the plate 30. The shaft 55 is then moved upwardly so that the rib 66 engages with the groove 39, after which the shaft 25 is rotated by the handle 107 in a direction such as to bring the zero of the dial 32 into coincidence with the projection 31. Rotation of the handle 107 causes the carriage 8 to move 4 mm. to the right (when viewing the machine in the direction of the movement of the blank 4). The same process is repeated with the rear carriage thereby moving the rear carriage 4 mm.

to the left (as viewed from the front of the machine). Hence when the machine is in use two fold lines are produced on the blank 4, one by the front carriage 8 and one by the rear carriage, the fold lines being 8 mm. apart.

It is to be understood that the machine described above is subject to modification without departing from the underlying principle. Thus a simpler mechanism could be employed, if only one thickness and quality of board or sheet is to be subjected to the fold line operation. In this case, the necessity for having two composite forming elements 131, 132, largely disappears. It becomes then possible to use a single upper forming member the periphery of which is of channel section so that the two flanges of the channel can engage on either side of the V-shaped lower forming element.

It will also be quite clear that the disposition of the upper and lower forming elements or members could be inverted.

The effect obtained in forming the fold lines is that shear slip planes are produced in the fibrous sheet or board in a zone along the fold line. Great moulding pressures are not required nor is the blank diminished significantly in the dimension perpendicular to the fold line. This seems to be due to the fact that when the material passes between the nip constituted by the upper and lower forming members or elements, a shearing force is exerted over the area of the material located on either side of the fold line and including the location of the fold line itself. The slip planes produced by the treatment can be seen after a blank has been prepared with the fold lines and experiment shows that if the shearing stress necessary to produce shear slip planes in a specimen of a board exceeds the tensile breaking stress of that board, then the particular sample of board in question is not suitable for the invention. This appears to be substantially the only limitation to the use of the machine.

Where fold lines are to be made in board of considerable thickness it is advantageous to make two closely adjacent fold lines for each bend or crease or complete turn-back that is to be performed with the material after the fold lines have been made therein. In producing for example a right angle bend, forty-five degrees of bend can be taken in each fold line so that in the finished bend the

material existing between the fold lines lies at an angle of a hundred and thirty five degrees to the walls approaching the right angled bend. By continuing the bending process beyond ninety degrees, a turn-down is formed in which the intermediate material lies at right angles to the superposed walls approaching the turn-down location.

We claim:

- 10 A machine for producing fold lines in sheet blanks made of fibrous material, the machine including at least one unit that comprises first, second and third rotary fold-line-forming members, a peripheral edge on each of the first and second fold-line-forming members for contacting one side of the sheet blank, a peripheral edge on the third fold-line-forming member for contacting the opposite side of the sheet blank, the peripheral edge of the first member lying in a first plane and the peripheral edge of the second member lying in a second plane that is inclined with respect to the first plane, the peripheral edge 15 of the third member lying in a third plane and the first and second rotary members lying on opposite sides of the third plane, the third rotary member comprising a disc having a bevelled peripheral portion on each side, the bevelled peripheral portions of the disc meeting to provide the said peripheral edge of the third rotary member, a sheet-supporting shroud ring on each side of the peripheral edge of the disc and rotatable therewith, the shroud rings respectively abutting against and masking the bevelled portions of the disc apart from its peripheral edge, and spring means supporting the shroud rings and urging them against the disc while permitting deflection of the shroud rings towards the axis of rotation of the disc comprising the third rotary member.
